UNITED STATES PATENT OFFICE.

WILLIAM L. CHURCH, OF NEWTON, MASSACHUSETTS.

DAM.

No. 799,829.

Specification of Letters Patent.

Patented Sept. 19, 1905.

Application filed June 2, 1905. Serial No. 263,448.

To all whom it may concern:

Be it known that I, WILLIAM L. CHURCH, of Newton, in the county of Middlesex and State of Massachusetts, have invented certain new and useful Improvements in Dams, of which the following is a specification.

This invention has especial reference to dams for reservoirs of waterworks where the quantity of overflow water is relatively small, 10 although it may be embodied in other dams, if desired.

The invention has for its object to prevent the wearing away or scouring of the stream-bed at the downstream side of the dam by the 15 impact of the overflowing water; and it consists in the improvements which I will now proceed to describe and claim.

The accompanying drawing represents a 20 perspective sectional view of a dam embodying my invention.

In the drawing, 12 represents the deck of the dam, which is preferably inclined from its heel 13 to its crest 14, so that the crest overhangs the deck and the deck overhangs the 25 heel.

15 represents a wear-resisting bed extending downstream from the heel of the dam, the width of the bed or its extension downstream from the deck being such that all the 30 overflow which passes over the crest of the dam falls upon the bed.

16 represents a baffle-wall which is located at the downstream side of the deck and is separated therefrom by a passage for overflow water, the said baffle-wall having a crest 35 17, which is preferably substantially flush with the crest of the deck and is separated from the latter by an opening containing transverse bars 18, forming a grid to prevent passage of logs, floating masses of ice, 40 &c., between the deck and the baffle-wall.

The opening between the baffle-wall and the deck is of sufficient width to accommodate all the overflow which normally passes over the 45 crest of the deck. The baffle-wall is arranged to deflect the said overflow backwardly toward the deck for two purposes—first, to reduce the force of the impact of the overflow water on the bed, and, secondly, to cause the stream 50 to impinge upon the portion of the bed adjacent to the deck. The bed is thus enabled to sustain the wear caused by the impact of the overflow against it, and at the same time its width or extension downstream from the 55 heel of the deck is enabled to be reduced to the minimum.

I have here shown the parts above described, excepting the bars 18, as composed of concrete reinforced by metal rods 20. Similarly-constructed buttresses 21 are provided at suitable intervals, the buttresses rising from the bed 15 and supporting the deck and the baffle-wall.

22 represents a beam of reinforced concrete which extends between the buttresses. 65

In case of a maximum overflow which cannot be accommodated by the passage between the deck and the baffle-wall the surplus water passes over the crest 17 of the baffle-wall and impinges on the lower or downstream portion 70 of the bed. The stream of surplus water is, however, cushioned by the stream deflected backwardly by the baffle-wall, so that the surplus water and any floating objects carried by it are not liable to injure the portion of 75 the bed on which they impinge.

23 represents a barrier which may extend between the buttresses to form a pool adapted to confine a body of water under the baffle-wall. 80

It will be seen that the described construction insures the substantially horizontal flow of the overflow water upon the unprotected bed of the stream below the wear-resisting bed 15, so that liability of the scouring and 85 washing of the unprotected portion of the bed is prevented.

I claim—

1. A dam having means at the downstream side of its crest for deflecting overflow water 90 backwardly.

2. A dam having means at the downstream side of its crest for deflecting overflow water backwardly, and a wear-resisting bed arranged to sustain the impact of the deflected 95 overflow water.

3. A dam comprising a deck, a wear-resisting bed extending downstream from the heel of the deck, and a baffle-wall located at the downstream side of the deck and adapted to 100 direct overflow water backwardly toward the deck and upon the bed.

4. A dam comprising a deck, a wear-resisting bed extending downstream from the heel of the deck, buttresses between the bed and 105 deck, and a baffle-wall supported by the buttresses at the downstream side of the deck and adapted to direct overflow water backwardly toward the deck and upon the bed.

5. A dam comprising a deck, a wear-resisting bed extending downstream from the heel of the deck, and a baffle-wall located at the 110

downstream side of the deck and separated from the latter by an overflow-passage.

6. A dam comprising a deck, a wear-resisting bed extending downstream from the heel 5 of the deck, a baffle-wall located at the downstream side of the deck and separated from the latter by an overflow-passage, and a grid or grating in the upper portion of said passage.

10 7. A dam comprising a deck, a wear-resisting bed extending downstream from the heel of the deck, a baffle-wall located at the downstream side of the deck and adapted to direct overflow water backwardly toward the deck 15 and upon the bed, the crest of the baffle-wall being substantially flush with the crest of the deck and located over the bed.

8. A dam having an upstream crest, a down-

stream crest separated from the upstream crest by an overflow-passage, and means for 20 deflecting backwardly the overflow passing through said passage, the deflected water cushioning the overflow passing over the downstream crest.

9. A dam having an upstream crest, a downstream crest, separated from the upstream crest by an overflow-passage, one side of which is formed by a baffle-wall below the downstream crest, and means for maintaining a cushioning-pool underneath the baffle-wall. 25 30

In testimony whereof I have affixed my signature in presence of two witnesses.

WILLIAM L. CHURCH.
